Patented Dec. 12, 1922.

UNITED STATES PATENT OFFICE.

NORMAN A. RANEY, OF TORONTO, ONTARIO, CANADA.

ROPE GRIP.

Application filed June 3, 1922. Serial No. 587,118.

To all whom it may concern:

Be it known that I, NORMAN A. RANEY, of the city of Toronto, in the county of York, Province of Ontario, Canada, a subject of the King of Great Britain, have invented certain new and useful Improvements in Rope Grips, of which the following is a specification.

This invention relates to rope grips for taking up the slack in ropes and more particularly to that type of rope grip having a pair of pivoted co-acting members and my object is to provide a device of this character which may be cheaply manufactured and yet be durable and efficient. A further object of my invention is to so construct the device that the rope may be easily and quickly released or tightened.

I attain my objects by means of the constructions hereinafter described and illustrated in the accompanying drawings in which—

Fig. 1 is a sectional view showing the rope grip in its operative position;

Fig. 2 a sectional view showing the rope grip in its inoperative position; and

Fig. 3 a plan view of Fig. 1.

In the drawings like numerals of reference indicate corresponding parts in the different figures.

The rope grip comprises a pair of co-acting clamping members 1 and 2 which are pivotally mounted on a U-shaped frame 3. The clamping member 1 formed as a lever is fulcrumed intermediate its ends on the rivet 4 which passes through the free ends of the U-shaped frame 3. This rivet also forms a transverse connection for the free ends of the U frame to prevent the ends spreading apart. One end of the lever is provided with an eye 5 by means of which the lever may be permanently connected with a suitable stationary part which might be a hook 6 or one end of a rope. On the other end of the lever 1 remote from the eye 5, is formed a toe 7.

The clamping member 2, formed as a dog, is fulcrumed intermediate its ends on the rivet 8 which passes through the sides of the U-shaped frame 3. The dog is formed with a heel 9 and a handle 10, these two parts extend rearwardly and have a recess 11 formed between them. The heel 9 and the toe 7 are cam shaped, the handle 10 is rearwardly curved and is provided with a guide 14, preferably formed as an eye, at its outer

end for the passage of the free end of a rope 6^a.

Referring to Fig. 1 it will be noted that the dog 2 is fulcrumed at a point substantially midway between the heel 9 and the handle 10 and opposite the recess 11 and that the heel is formed with a rope clamping surface 12. It will also be noted that the eye 5 and the heel 9 are located at one side of an imaginary line passing through the centres of the pivots 8 and 4 and the handle 10 is located at the other side of said imaginary line when the device is in its rope gripping position. The lever 1 is adapted to be swung on its pivot so that the toe 7 may be brought into a co-operative position with the rope clamping surface 12 whereby the periphery of the toe is used to co-act with the rope clamping surface to securely hold the rope and, with the handle 10, to limit the movement of the dog relative to the toe. From the above description it is evident that, when the toe 7 of the lever 1 is moved away from the clamping surface 12, the free end of the rope 6^a may be passed over the heel 9 and between the latter and the toe 7 and then through the eye 14, (see Fig. 2) and when the rope is pulled to the desired tension the tension in the rope will cause the members 1 and 2 to swing to their co-operating position and thus jam the rope and securely hold it between the toe 7 and the rope clamping surface 12 as hereinbefore described. The dog 2 is also formed as a lever, in effect, whereby as the pull on the heel 9 is increased, the dog will tend to rock on its pivot and thus cause the rope to be jammed tighter between the co-acting clamping surface 12 and the toe 7.

It is desirable to guide the rope over the heel 9 and also to facilitate the passage of the rope between the heel 9 and the toe 7 when the gripping members are rocked to their inoperative position. For this purpose I form the groove 15 on the heel 9, which groove extends from a point on the forward face of the heel around to the rope clamping surface 12. The toe 7 is also formed with a groove 16 extending across the upper face thereof, around the forward face and gradually dies out as it comes opposite the part of the handle 10 which engages the toe 7. With this construction, the dog may be actuated to rock the lever 1 to its inoperative position and thus bring the grooves 15 and 16 into a position of co-

operation to form a passageway for the rope which may be easily passed therethrough and then through the eye 14. Referring to Fig. 2 it will be noted that when the parts 5 are in the position shown, the rope may be easily slackened or tightened around the heel 9 without undue friction and that a simple movement of the free end of the rope will 10 swing the dog to its position of co-operation with the lever 1. The end of the U-shaped member 3 is adapted to engage the handle 10 to limit the movement of the dog 2 in one direction whereby a portion of the groove 15 will always be tangent to the rope.

15. What I claim as my invention is:

1. A rope grip comprising a connecting frame; and a pair of co-acting rope clamping members pivotally mounted on the connecting frame, one of the members having 20 one end adapted to be secured to a stationary part and having a toe formed on the other end, the second member having a surface for clamping the rope forced towards it by the said toe and said second member also having a part formed 25 thereon adapted to engage one of the other parts at a point distant from the rope clamping surfaces for limiting the movement of the second members.

30. 2. A rope grip comprising a connecting frame; and a pair of co-acting rope clamping members pivotally mounted on the connecting frame, one of the members having one end adapted to be secured to a 35 stationary part and having a toe formed on the other end, the second member having a surface for clamping the rope forced towards it by the said toe and said second member also having a part formed thereon 40 adapted to engage the first mentioned member at a point distant from the clamping surfaces for limiting the movement of the second member.

45. 3. A rope grip comprising a connecting frame; a lever pivoted on said frame having one end adapted to be connected with a stationary part and having a toe formed on the other end; and a co-acting member pivoted on said connecting frame and having 50 a surface for clamping a rope forced toward it by the said toe and having a heel over which the rope passes to swing the parts to their co-operating position, said co-acting member also having a part formed thereon 55 adapted to engage one of the other parts at a point distant from the rope clamping surfaces for limiting the movement of the co-acting member.

60. 4. A rope grip comprising a connecting frame; a lever pivoted on said frame having one end adapted to be connected with a stationary part and having a toe formed on

the other end; and a co-acting member pivoted on said connecting frame and provided with a heel and a handle, the heel having 65 a surface formed thereon for clamping the rope forced towards it by the said toe, the handle adapted to engage one of the other parts for limiting the movement of the co-acting member.

70. 5. A rope grip comprising a connecting frame; a lever pivoted on said frame having one end adapted to be secured to a stationary part and having a cam shaped toe formed on the other end thereof, the toe 75 being provided with a grooved periphery; a co-acting member pivoted on said connecting frame and provided with a cam shaped heel having a groove formed in its periphery for guiding a rope and having a 80 surface formed thereon for clamping the rope forced towards it by the said toe; and a handle formed on the co-acting member adapted to engage one of the other parts for limiting the movement of the co-acting 85 member, the toe being adapted to be engaged by the said heel whereby the co-acting member may be moved to rock the toe away from the clamping surface to bring the grooves into a co-operative position.

90. 6. A rope grip comprising a connecting frame; a lever pivoted on said frame having one end adapted to be secured to a stationary part and having a cam shaped toe formed on the other end thereof, the toe 95 being provided with a grooved periphery; a co-acting member pivoted on said connecting frame and provided with a cam shaped heel having a groove formed in its periphery for guiding a rope and having a surface formed 100 thereon for clamping the rope forced towards it by the said toe; and a handle formed on the co-acting member adapted to engage one of the other parts for limiting the movement of the co-acting member and 105 having a guide formed therein through which the end of the rope may pass, the toe being adapted to be engaged by the said heel whereby a pull on the rope will 110 actuate the heel to rock the toe away from the clamping surface to bring the grooves into a co-operative position.

115. 7. A rope grip constructed as set forth in claim 3 in which the connecting end of the lever and the heel of the co-acting member are located at one side of an imaginary line passing through the centres of the pivots and the part for limiting the movement of the co-acting member being located at the other side of said imaginary line.

Signed at Toronto, Ontario, this 31 day of May, 1922.

NORMAN A. RANEY.
